(57) **CLAIM**

The ornamental design for a pack for pasta, as shown and described.

DESCRIPTION

FIG. 1 is a perspective view of a pack for pasta, showing my new design;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The uneven length broken lines illustrate boundaries of unclaimed subject matter and form no part of the claimed design. The even length broken lines illustrate portions of the pack for pasta that form no part of the claimed design.

1 Claim, 7 Drawing Sheets
